(57) **CLAIM**

The ornamental design for a digital audio disc player with radio tuner for automobile, as shown and described.

DESCRIPTION

FIG. 1 is a front, left side, perspective view of a digital audio disc player with radio tuner for automobile showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom view thereof; and,

FIG. 8 is a front, right side perspective view showing the digital audio disc player with radio tuner for automobile in an alternate position of use.

The broken lines in the drawing figures represent portions of a radio that form no part of the claimed design.

It is certified that error appears in the above-identified patent and that said Letters Patent is hereby corrected as shown below:

On the title page delete the old existing drawing and replace it with the new drawing on the title page that should be inserted as illustrated.

On the Title Page:

On the title page, Item (57) Claim, line 2, after the word automobile, the “,” should be removed.

On the title page, Item (57) Description, line 5, “Fig. 3 is a rear view thereof;” should be cancelled per examiner’s amendment.

On the title page, Item (57) Description, line 6, “Fig. 4 is a left side view thereof” should be **--Fig. 3 is a left side view thereof--**.

On the title page, Item (57) Description, line 7, “Fig. 5 is a right side view thereof;” should be **--Fig. 4 is a right side view thereof;--**.

On the title page, Item (57) Description, line 8, “Fig. 6 is a top plan view thereof;” should be **--Fig. 5 is a top plan view thereof;--**.

On the title page, Item (57) Description, line 9, “Fig. 7 is a bottom view thereof; and,” should be **--Fig. 6 is a bottom view thereof; and,--**.
